UNITED STATES PATENT OFFICE.

LEROY S. PFOUTS, OF CANTON, OHIO.

CRUSHING-MACHINE.

SPECIFICATION forming part of Letters Patent No. 594,964, dated December 7, 1897.

Application filed April 13, 1896. Serial No. 587,354. (No model.)

To all whom it may concern:

Be it known that I, LEROY S. PFOUTS, a citizen of the United States, residing at Canton, in the county of Stark and State of Ohio, have 5 invented certain new and useful Improvements in Crushing-Machines; and I do hereby declare that the following is a full, clear, and exact description of the same, reference being had to the annexed drawings, making 10 a part of this specification, and to the figures of reference marked thereon, in which—

Figure 1 is a side elevation of the crusher. Fig. 2 is a vertical section showing the arrangement and location of the different parts. 15 Fig. 3 is a top view. Fig. 4 is a side view of the pitman, showing a transverse section of the crusher-jaw lever. Fig. 5 is an edge view of the pitman, showing the crusher-jaw lever properly connected to the lever. Fig. 6 is an 20 edge view of the movable crushing-jaw. Fig. 7 is a view showing the rear side of the movable crushing-jaw. Fig. 8 is an edge view of the upper toggle-bar. Fig. 9 is a side view of the upper toggle-bar. Fig. 10 is a top view 25 of the crusher-jaw lever.

The present invention has relation to crushing-machines; and it consists in the different parts and combination of parts hereinafter described, and particularly pointed out in the 30 claims.

Similar figures of reference indicate corresponding parts in all the views of the drawings.

In the accompanying drawings, 1 represents the frame of the machine proper, which is formed of sufficient weight and strength to carry out the purposes and objects herein-after described, said base or frame being securely seated upon a suitable foundation 35 such as is commonly used in crushing-machines of this class. To the base or frame 1 is properly journaled the cross-shaft 2, which cross-shaft is provided with the balance-wheels 3 and the power-wheel 4, all of said 40 wheels being securely attached to the cross-shaft in any convenient and well-known manner. To the cross-shaft 2 is connected the eccentric 5, to which eccentric is connected the top or upper end of the pitman 6 45 by means of the cap 7. For the purpose hereinafter described the pitman 6 is formed open, so as to provide a means for properly con-

necting the jaw-lever 8, said jaw-lever being provided with the rib 9, which rib is properly seated into the bearing 10, said bearing being properly attached to the bottom or lower portion of the pitman 6, as illustrated in Fig. 2.

For the purpose of preventing any accidental displacement of the lever 8 the springs 11 are provided and are located side by side between the top or upper side of the lever 8 and the upper portion of the pitman 6, substantially as illustrated in Figs. 2 and 4. The lever 8 is fulcrumed upon the cross bolt or bar 12, which bar is properly connected to the frame 1 or its equivalent. The lever 8 is provided with the groove 13, which groove is located a short distance above the cross bolt or bar 12 and a short distance in front of the vertical center of the cross bar or bolt 12, as illustrated in Fig. 2. Within the groove 13 is seated one edge of the toggle-lever 14, which toggle-lever is located between the lever 8 and the bottom or lower end of the crushing jaw or head 15, said toggle-lever being held in proper position with reference to the crusher jaw or head by means of the cross-groove 16. The lever 8 is extended a short distance in front or forward of its pivotal point and is provided with an aperture 17, through which 80 aperture is passed the cross-bolt 18, which cross-bolt pivotally connects the bottom or lower ends of the links 19, which links extend upward and are pivotally connected to the top or upper end or portion of the jaw 15 85 by means of the cross-bolt 20, which cross-bolt also pivotally connects the arm or bar 21, said arm or bar 21 being pivotally connected to the frame or base 1 by means of the cross-bolt 22.

For the purpose of holding the jaw 15 in proper position with reference to the plate 14 the rod 23 is provided, which rod is connected to the rear side of the jaw 15 and extends rearward between the side members of the pitman 6 and the springs 11 and is connected to the rear end of the body 1.

For the purpose of providing a sufficient amount of elasticity to the parts the rod 23 is provided with the buffer 24, which buffer is located between the rear end of the frame 1 and suitable washers or nuts located upon the end of rod 23, and for the purpose of providing proper adjustment the rear end of the rod

23 should be screw-threaded for a short distance.

5 The operation of the crusher proper is as follows: As the eccentric 5 is elevated by the rotation of the cross-shaft 2 the pitman 6 will be moved up, carrying with it the rear end of the lever 8, which in turn depresses the front or forward end of said lever, carrying with it the links 19, thereby moving the crushing-jaw 15 downward and at the same time moving the lower end of the jaw forward by means of the toggle-levers 14, said toggle-levers being located above the fulcrumed point of the lever, which causes the toggle-lever 14 15 to force the crushing-jaw forward during its downward movement. The top or upper end of the crushing-jaw will be moved slightly forward, owing to the arc described by the forward end of the arm or bar 21, said arm 20 or bar being so located that it will not be brought below a horizontal position, thereby preventing any backward movement of the crusher-head during the time it is being forced downward, thereby forcing the crushing-jaw 25 15 forward throughout its entire length and at the same time moving the bottom or lower portion of the crushing-jaw farther forward than its top portion. As the pitman 6 is lowered the forward portion of the lever 8 will be 30 elevated, thereby elevating the crushing-jaw and at the same time carrying it backward or away from the fixed jaw 25, said fixed jaw being securely connected to the frame 1. It will be understood that the jaw 15 is to be provided with the ordinary crushing-plate 26, which is attached in any convenient and well-known manner, inasmuch as it is immaterial how the plate is attached except that it must be rigidly and firmly connected to the jaw or head 15.

Having fully described my invention, what I claim as new, and desire to secure by Letters Patent, is—

1. The combination of the machine-frame 45 carrying a cross-shaft having an eccentric, a pitman operated by the eccentric, a fulcrumed lever having a connection with the pitman, a movable crushing-jaw supported by links, said links being connected to the fulcrumed 50 lever and to the crushing-jaw, a toggle-lever having its bearing between the lever and crushing-jaw and above the pivoted connection of the lever, and an arm or bar loosely connected to the machine-frame and to the crushing-jaw, substantially as described.

55 2. The combination of the supporting-frame provided with a cross-shaft having an eccentric, a pitman carrying a lever at its lower portion, springs located between the upper

side of the lever and the upper portion of the 60 pitman, and links pivotally connected to the lever in front of the pivotal connection of said lever, a toggle-lever located between said lever and the crushing-jaw, and an arm connected to the crushing-jaw and to the machine-frame, substantially as and for the purpose specified.

3. In an ore-crushing machine, the combination with the frame thereof, of a crushing-jaw linked to said frame, a horizontal rod connected to the crushing-jaw and to the said frame, a fulcrumed lever having a linked connection with the crushing-jaw, a toggle-lever located between the crushing-jaw and fulcrumed lever and means for rocking the latter-named lever, substantially as described.

4. In an ore-crushing machine, the combination with the frame thereof, of a crushing-jaw having a linked connection between its upper portion and the frame of the machine, 80 a rocking lever, vertically arranged links connecting said lever and crushing-jaw, and a toggle-lever between the crushing-jaw and rocking lever, substantially as described.

5. In an ore-crushing machine, the combination with the supporting-frame provided with a cross-shaft carrying an eccentric, of a slotted pitman operated by the eccentric, a lever pivoted near one end to the supporting-frame and having its rear end located in the slotted portion of the pitman, a crushing-jaw, a cross-shaft 22 mounted upon the supporting-frame, arms journaled upon said shaft and having their forward ends connected to the crushing-jaw, a connection between the short arm of the rocking lever and the upper portion of the crushing-jaw, and a toggle-lever bearing against the lower portion of the crushing-jaw, and against the rocking lever, substantially as described.

100 6. In a crushing-machine the combination of the frame provided with a cross-shaft having an eccentric, a slotted pitman, a lever having its free end located in the slotted portion of the pitman and seated therein, springs located above the lever, and the lever fulcrumed to one side of the pitman, and a movable crushing-jaw linked to the machine-frame and lever, substantially as and for the purpose specified.

105 In testimony that I claim the above I have hereunto subscribed my name in the presence of two witnesses.
